ATTORNEY

UNITED STATES PATENT OFFICE.

LILLIAN S. CANDIA, OF NEW YORK, N. Y.

DESIGN FOR A DOLL.

Application filed July 23, 1924. Serial No. 10,229. Term of patent 7 years.

To all whom it may concern:

Be it known that I, LILLIAN S. CANDIA, a citizen of the United States, residing at the borough of Manhattan, city, county, and State of New York, have invented a new, original, and ornamental Design for Doll, of which the following is a specification, reference being had to the accompanying drawing, forming a part thereof.

Fig. 1 is a front elevation of a doll embodying my invention; and

Fig. 2 is a side elevation of said doll.

I claim:

The ornamental design for a doll, as shown.

LILLIAN S. CANDIA.

Witnesses:

HELEN V. WHIDDLER,
JULIUS M. LUTZ.
